UNITED STATES PATENT OFFICE.

JOSEPH WILLIAMS, JR., OF PITTSBURGH, PENNSYLVANIA, ASSIGNOR TO PITTSBURGH CHEMICAL COMPANY, OF PITTSBURGH, PENNSYLVANIA, A CORPORATION OF PENNSYLVANIA.

FEED DEVICE FOR LIQUIDS.

1,098,203.

Specification of Letters Patent. Patented May 26, 1914.

Application filed July 15, 1912. Serial No. 709,449.

To all whom it may concern:

Be it known that I, JOSEPH WILLIAMS, Jr., a citizen of the United States, residing at Pittsburgh, in the county of Allegheny and 5 State of Pennsylvania, have invented certain new and useful Improvements in Feed Devices for Liquids, of which the following is a specification.

My invention has for its object to provide 10 means for supplying a measured quantity of liquid to a boiler or other utilizing apparatus, preferably in connection with a forced feed mechanism, as an injector.

It comprises a reservoir for the liquid 15 provided with circulating conduit pipes adapted for connection with an injector or the like by introducing a forced feed by suction, a controlling device for regulating the rate of flow, a connection therefrom to the 20 main feed line, and a supplemental connection connected therewith, adapting the device to be used independent of the flow regulating the controlling device and to discharge into the main conduit a materially 25 larger volume of the liquid from time to time as desired.

The device is particularly designed for the purpose of supplying a boiler compound in limited and regulable quantities whereby 30 the compound may be supplied in the boiler as wanted, or to suit the quality of the water being used.

Preferred constructions of the invention are shown in the drawings, in which—
35 Figure 1 is a view of the device in side elevation. Fig. 2 is a vertical sectional view taken transversely through Fig. 1. Fig. 3 is a detail sectional view showing the circulation controlling cock set to communicate 40 with the main reservoir and measuring tube. Fig. 4 is a view similar to Fig. 2, showing a modified arrangement, eliminating the controlling device for the drop-by-drop feed. Fig. 5 is a horizontal sectional view on the 45 line V. V. of Fig. 2. Fig. 6 is a partial sectional view of the lower part of the device showing a modified construction. Fig. 7 is a similar view showing a connection from the reservoir to a forced feed device. 50 The reservoir 2 for the liquid compound is made of sheet or cast metal in square, cylindrical, or other preferred form, having a top 3 and bottom 4. The interior fluid-containing cavity 5 is filled with the 55 liquid through a charging opening 6 hav-

ing a removable cap 7 and may be drained from the bottom by gravity by any suitable connection.

Extending from a point adjacent to the bottom of the reservoir 2 upwardly through the top 3, or in any other suitable manner, is a feed pipe 8 communicating with a glass measuring tube 9 through a suitable coupling 10 and a valve casing 11 having a downwardly extending terminal dropper 12. 60 A needle valve 13 is adjustably mounted with relation to the tapered interior of dropper 12 by threaded stem 14 mounted in the valve casing, having a suitable stuffing box 15 and a finger terminal 16. By this means the 65 rate of flow through the dropper 12 can be accurately controlled. A similar needle or other suitable valve 17 admits a limited supply of air to the interior of valve casing 11, or may be used to entirely close communication 70 from the atmosphere thereto. A supply pipe 18, which may be connected with an injector or other forced feed device, communicates with measuring tube 9 and also with the bottom of the reservoir by branch 75 pipes 19 and 20, respectively, at each side of a three-way cock or valve 21 mounted in a suitable valve casing and connected with said circulating pipes with suitable fittings.

In the ordinary operation of the device, 80 for the purpose of supplying a drop-by-drop feed to pipe 18, the valve or cock 21 is turned to the position shown in Fig. 2, establishing communication from the tube 9 to pipe 18. Thereupon suction in pipe 18 85 will induce a flow of the liquid from reservoir 2 upwardly through a pipe 8 and valve 11 in the desired amount as regulated, the operation continuing as long as suction continues or until the supply is exhausted. 90 When it is desired to discharge into pipe 18 a larger volume of the liquid, as, for instance, an ounce or more, valve 21 is turned to the position indicated in Fig. 3, establishing communication direct from the reservoir through pipe 20 and said valve, the liquid rising in measuring tube 9 to the same level as that in the reservoir 2. Upon reversing the valve 21 to the position shown in Fig. 2 such measured amount will be discharged downwardly into pipe 18 and immediately carried to the boiler. In Fig. 4 100 I have shown a construction in which the latter operation just described is provided for only, without the drop-by-drop feed. 105 110

In such case the measuring tube 9' is merely mounted in communication with reservoir 2' through valve 21' and pipe 20' and the other connecting fittings at the top, the upper end of tube 9' being merely connected in the manner shown by ordinary commercial fittings, as elbows 11' and 10' and the pipe sections. These, however, have no other function than that of merely providing a convenient and mechanical mounting for the tube 9', which serves as a sight tube. An air supply cock or valve 17' may, however, be used in the manner indicated, if desired, to supply air to the tube and reservoir.

In Fig. 6 I show an arrangement in which the reservoir 2^a is connected with the sight tube 9^a through a lower connection 19^a embodying a controlling valve 11^a, by which the sight tube may be entirely cut off if desired. Direct supply connection to the boiler is provided by pipe 18^a embodying a measuring valve 21^a adapted to discharge a measured quantity of the liquid to the boiler from time to time. For such purpose the valve body 23^a is provided with a pocket 24^a adapted to register with the interior of the reservoir when turned up and to be turned down to discharge into the boiler, as shown in the drawing. In order to effect a free discharge of the measured liquid from pocket 24^a it is provided with a small air port 25^a adapted to register with the atmosphere through port 26^a when the pocket is reversed, as shown.

In Fig. 7 I show the supply pipe 18^b leading from reservoir 2^b directly through controlling valve 21^b and connected with a force feed device 27^b as an injector, having a water supply connection 28^b, a steam jet supply 29^b and a delivery pipe 30^b leading to the boiler. By this means the valve 21^b may be set to control the flow and the feed of the liquid is accurately regulated and positively effected by direct connection to the injector.

The construction and operation of the device will be readily understood from the foregoing description. It enables the operator to accurately control and observe the operation of the feed at all times so as to avoid waste or insufficient supply. It operates to feed during maintenance of suction and to

automatically cease operation upon cessation of operation and to deliver the liquid in minute quantities or in a considerable volume from time to time, as desired.

The device is comparatively simple in construction, reliable and efficient in operation and not liable to get out of order, and effects a material economy in the use of the compound, while providing for accurate regulation to suit local conditions as to the character of the water being supplied to the boiler, etc. It may be made in various sizes, proportions, or designs to suit the conditions or requirements of use, and the invention may be changed or varied by the skilled mechanic without departure from the scope of the following claims.

What I claim is:

1. In a feed device for liquids, the combination of a reservoir, a connection to the base of the reservoir, a connection to the reservoir extending outside above the normal line of liquid therein and embodying a measuring tube, a downwardly extending suction tube, and a three-way valve connected with said connections and with the suction pipe adapted to establish communication from one of said connections to the other or from either to the suction pipe, substantially as set forth.

2. In a feed device for liquids, the combination of a reservoir, a connection to the base of the reservoir, a connection to the reservoir extending outside above the normal line of liquid therein and embodying a measuring tube, a circulation controlling valve in said connection at the upper portion of said measuring tube adapted to deliver a limited supply of liquid through the measuring tube, a downwardly extending suction tube, and a three-way valve connected with said connections and with the suction pipe adapted to establish communication from one of said connections to the other or from either to the suction pipe, substantially as set forth.

In testimony whereof I hereunto affix my signature in the presence of two witnesses.

JOSEPH WILLIAMS, JR.
